CAL A. FORNEY, OF GOSHEN, INDIANA, ASSIGNOR TO THE FIRST NATIONAL BANK OF PERU, INDIANA, TRUSTEE.

IRONING TABLE

Application filed July 6, 1926. Serial No. 180,726.

The invention relates to improvements in foldable supporting means for ironing boards and it is the object of such invention to provide a new and improved construction and arrangement of parts which will be exceptionally simple and inexpensive, yet will be efficient, reliable, and in every way desirable.

With the foregoing in view, the invention resides in the novel subject matter herein-after described and claimed, the description being supplemented by the accompanying drawings.

Figure 1 is a side elevation showing the board in condition for use.

Figure 2 is an end elevation.

Figures 3 and 4 are detail transverse sections on lines 3-3 and 4-4 of Figure 1.

Figure 5 is a side elevation and Figure 6 a bottom plan view, both showing the supporting structure in folded position.

The numeral 7 designates an ironing board of conventional shape, but provided with the new and improved supporting means, constituting the present invention. The numerals 8 have reference to a pair of legs at one end of the board, suitably connected by braces 8' and pivoted to said board at their upper ends, so that they may be upwardly folded, as shown in Figures 5 and 6. The pivotal connections between the legs 8 and the board 7, are of novel form and include a pair of vertical lugs 9 carried by said board, these lugs being preferably formed by downwardly bending the ends of a transverse bar 10 which is suitably secured to the lower side of said board. The remaining portions of these pivotal connections can best be described after first explaining other features of construction.

The numbers 11 designate two braces which are pivoted at 12 to the legs 8, between the ends of the latter, said braces inclining toward the board 7 and having a sliding connection with the latter, which permits movement of said braces away from the lugs 9, when the legs 8 are upwardly swung, said sliding connection normally preventing movement of the legs 8 in the opposite direction. This sliding connection preferably comprises a wire bail 12 carried by the upper ends of the braces 11, and a longitudinal track 13 secured to the lower side of the board 7, said track slidably suspending said bail. The ends of the wire, from which

the bail 12 is formed, are preferably extended laterally outward through openings 14 in the braces 11 and are then bent downwardly and inwardly as at 15, so as to establish an effective connection between the braces and the bail, permitting slight pivotal movement of said bail. The track 13 may well be formed from a flat metal bar having its major portion downwardly spaced from the board 7, the ends of said bar however being upwardly offset and secured to the board by appropriate fasteners 16.

A third leg 17 inclines toward the legs 8 and is pivoted at its upper end to the board 7, at a point between the upper ends of the braces 11 and legs 8. The pivot for this leg 17, may well be formed by passing a short length of wire 18 through the leg and through suitable lugs 19 which are secured to and project downwardly from the board 7, the ends of the wire 18 being laterally bent to prevent withdrawal of said wire. The leg 17 is upwardly foldable, but provision is made for normally holding it against such movement. Moreover, the braces 11 are provided with stop means normally engaging the lower edge of said leg 17, so that said braces 11 cannot move in leg-folding direction, and permit upward swinging of the legs 8, until said leg 17 has been upwardly swung. To attain this end, I prefer to provide a single transverse bar 20 secured at its ends to the braces 11, by appropriate fasteners 21. These braces are disposed at opposite sides of the leg 17 and the bar 20 normally abuts said leg, as shown in Figure 1. Thus, movement of the braces 11 in a direction which would permit folding of the legs 8, is not permitted, as long as the leg 17 is held in its operative position.

To hold the leg 17 in effective position, I make use of a U-shaped brace rod 22 whose intermediate portion is engageable with a notch 23 or some equivalent shoulder formed on the leg 17, the latter being preferably provided also with a guide 24 for said intermediate portion of the brace rod. The ends of this rod are bent laterally outward as at 25 and are passed through openings in the lugs 9 and legs 8, thereby establishing pivotal connections between said legs and lugs and also pivotally mounting the brace rod 22. To hold the pivots 25 in proper position, their outer ends are suitably bent, as indicated at 26.

When the device is to be folded, the brace rod 22 is released from the shoulder or notch 23, permitting the leg 17 to swing toward the board 7. Then as this leg 17 is disengaged from the bar 20, the legs 8 may be inwardly swung toward the board 7, and during this movement, the sliding connection 12-13 comes into play to permit sliding of the braces along the lower side of the board, so that the entire supporting structure will then lie in close proximity with the board and the device may be stored in small space. When extending the device for use, the legs 8 are first swung downwardly, thereby positioning the braces 11 as shown in Figure 1. Then, the leg 17 is downwardly swung and abuts the bar 20 so as to hold the braces 11 and legs 8 against inward movement. When the rod 22 is engaged with the shoulder 23, the leg 17 cannot swing to an inoperative position and consequently the entire supporting structure will be effectively held in condition for use.

It will be seen from the foregoing that while the invention is rather simple and inexpensive, it will be efficient and reliable, forming a rigid structure when extended for use and permitting compact folding whenever desired.

Excellent results are obtainable from the details disclosed and they are therefore preferably followed. However, within the scope of the invention as claimed, variations may be made.

35 I claim:—

1. In an ironing table, a board, means for supporting said board comprising a pair of supporting legs pivoted to one end of the board for upward folding, braces pivoted to said legs and inclining therefrom to the board, means connecting the upper ends of said braces to the board and permitting sliding of the braces in a direction away from the leg pivots when the legs are upwardly folded, a third leg declining away from the first named legs and pivoted to the board at a point between the upper ends of said braces and said first named legs, said third leg also being upwardly foldable toward the board, stop means on said braces abutting the lower edge of said third leg to prevent movement of said braces to their folded position until the third leg is folded, and releasable means for normally holding said third leg against folding.

2. A structure as specified in claim 1; said connecting means comprising a bail having its ends bent laterally and passing through the upper ends of said braces and then around the sides of the braces and a track comprising a bar extending longitudinally of and having its ends upwardly offset and secured to the board, said bail being slidably supported by said track.

3. A structure as specified in claim 1; said releasable means comprising a U-shaped brace rod having its ends bent laterally, lugs projecting downwardly from the board and with which said laterally bent ends of the brace rod are pivotally engaged, said bent ends also forming pivotal connections for said pair of legs, and having their extremities bent at an angle for holding the legs in place, a shoulder on said third leg with which the intermediate portion of said brace rod is engaged and a guide on the third leg over the intermediate engaging portion of said brace rod.

4. In an ironing table, a board, an upright leg member pivotally connected to the board adjacent one of its ends to fold up and under the same, an inclined leg member pivoted to the board in spaced relation to the upright leg member and adapted to fold in the same direction as the latter, a brace member pivoted to upright leg member and crossing the inclined leg member, a slideable connection between the brace member and the board to permit folding of the brace and the upright leg member, stop means on an intermediate part of the brace member to engage an intermediate part of the inclined leg member and limit its downward swinging movement, and a second brace member crossing the first named brace member and having a releasable engagement with the inclined leg member for locking the latter in operative position.

5. In an ironing table, a board, a pair of vertical lugs on the board, a pair of legs, bracing means for said legs, a third leg pivoted to the board and a U-shaped brace rod for the third leg, the ends of said rod being bent laterally and passed through the lugs and the first named legs to pivot the latter to the former, and to pivotally mount said brace rod.

In testimony whereof I have hereunto affixed my signature.

CAL A. FORNEY.
